(57) **CLAIM**

The ornamental design for an exercise device as shown and described.

DESCRIPTION

FIG. 1 is an upper front perspective view of the exercise device embodying my new design;

FIG. 2 is a lower rear perspective view thereof;

FIG. 3 is a front side elevation view thereof;

FIG. 4 is a rear side elevation view thereof;

FIG. 5 is a right side elevation view thereof, the left side elevation view being a mirror image of FIG. 5;

FIG. 6 is a top plan view thereof;

FIG. 7 is a bottom plan view thereof; and,

FIG. 8 is a right side elevation view of the exercise device shown in a state of use thereof.

The dashed lines in FIG. 8 form no part of the claimed design and represent the unclaimed environment.
